(57) **CLAIM**

The ornamental design for a fitting for tire inflation and tire repair, as shown and described.

DESCRIPTION

FIG. 1 is a front view of my new design for a fitting for tire inflation and tire repair;

FIG. 2 is a rear view thereof;

FIG. 3 is a right side view thereof;

FIG. 4 is a left side view thereof;

FIG. 5 is a top view thereof; and,

FIG. 6 is a perspective view thereof.

Features shown in broken lines show environmental structure and form no part of the claimed design.

1 Claim, 5 Drawing Sheets
